RAILWAY SWITCH ROD CONNECTING MEANS

Filed May 3, 1941

UNITED STATES PATENT OFFICE

2,316,312

RAILWAY SWITCH ROD CONNECTING
MEANS

Herbert L. Bone, Forest Hills, Pa., assignor to
The Union Switch & Signal Company, Swiss-
vale, Pa., a corporation of Pennsylvania

Application May 3, 1941, Serial No. 391,780

3 Claims. (Cl. 287—97)

My invention relates to railway switch rod connecting means, that is, to means for connecting any of the rods which serve to maintain the proper relative spacing between the movable points of a railway switch or movable point frog with the switch or frog points.

One object of my invention is to provide new and improved connecting means of the type described which will permit sufficient angular movement between the switch rods and the movable switch points to prevent the development of high stresses in the switch rods or associated parts due either to creepage of the points, or to the motion of the points which normally occurs when the switch is reversed.

Another object of my invention is to provide a connecting means of the type described including a swivel joint which can be kept sufficiently tight to avoid the development of objectionable lost motion.

A further object of my invention is to provide a connecting means employing a minimum number of parts which are inexpensive to manufacture and easy to assemble.

A further object of my invention is to provide a connecting means which will prevent undesirable tipping or rolling of the points.

According to my invention, each switch rod is provided at each end with an upstanding arm having a vertically disposed semicylindrical bearing surface which mates with the correspondingly shaped outer surface of an offset portion formed in a bearing bracket bolted or otherwise secured to the adjacent switch point. The inner surface of the offset portion of each bearing bracket is concentric with the outer surface, and extending through aligned holes provided in the offset portion and the adjacent switch rod arm is the shank of a bolt, the head of which is rounded to form a bearing surface which cooperates with the inner surface of the offset portion of the bearing bracket. Each bolt is provided at its threaded end with a lock washer and with a nut which serves to secure the switch rod to the bearing bracket to thereby form a connecting means which is free to swivel in response to the normal movement of the switch points, but which is prevented from swiveling in the direction to permit rolling of the switch points.

Other objects and characteristic features of my invention will become apparent as the description proceeds.

I shall describe two forms of connecting means embodying my invention, and shall then point out the novel features thereof in claims.

In the accompanying drawing, Fig. 1 is a top plan view showing a railway switch provided with a head and front rod connected with the switch points by connecting means constructed in accordance with my invention. Fig. 2 is a front end

view of the switch shown in Fig. 1. Figs. 3 to 5, inclusive, are detail views of various parts comprising the connecting means embodying my invention.

5 Similar reference characters refer to similar parts in each of the several views.

Referring first to Figs. 1 and 2, the reference character A designates a railway switch comprising, as usual, two fixed rails 1 and 1a and two movable switch points 2 and 2a. The fixed rails 1 and 1a are laid on tie plates 3, and are secured to crossties 4 in the usual manner.

Connected to the movable switch points by connecting means embodying my present invention are switch rods 5 and 6 generally referred to as front and head rods, respectively. These rods, except for their end portions, may have any conventional construction, and as here illustrated they are made in longitudinally adjustable sections with an insulated joint in the middle. The switch rod 5 is connected through the medium of the usual switch basket 7 with the usual lock rod 8, while the head rod 6 is similarly connected to an operating rod 9, whereby the switch points

15 may be moved to their normal and reverse positions. When the switch occupies its normal position, in which position it is shown in Fig. 1, the switch point 2 engages the fixed rail 1, and the switch point 2a is spaced a predetermined distance from the fixed rail 1a. When, however, the switch is reversed, the switch point 2a then engages the fixed rail 1a, and the switch point 2 is spaced from the fixed rail 1.

According to my present invention, each switch rod is provided at each end with an upstanding arm 10 which is pierced by a horizontally extending through hole 10a, and which is provided on the side nearest the associated switch point with a vertically disposed semicylindrical bearing sur-

30 face 10b. Each bearing surface 10b mates with a correspondingly shaped bearing surface 12a formed on the outer side of a rounded offset portion 12b provided in an associated bearing bracket 12 bolted by means of bolts 13 to the

35 switch point 1 or 1a as the case may be. The inner surface 12c of the offset portion 12b of each bearing bracket 12 is concentric with the outer surface, and comprises a second bearing surface which mates with a correspondingly

40 shaped bearing surface 14a formed by rounding one side of the head of an associated clamping bolt 14. The shank of each clamping bolt 14 extends through the hole 10a in the associated arm 10 and through an aligned hole 12d formed in

45 the associated offset portion 12b, and is provided at its threaded end with a lock washer 15 and with a nut 16 which serve to secure the switch rod to the bearing bracket. As best seen in Fig. 4, the hole 12d is elongated to provide clearance 50 on either side of the bolt 14. The width of the

hole 12d in the other direction, however, is just sufficient to permit the bolt 14 to be readily inserted into the hole. The nuts 16 are tightened sufficiently to prevent end play between the switch rods and the associated bearing brackets, but not tightly enough to prevent the parts from swiveling about the concentric bearing surfaces in response to creepage of the switch points or to the movement of the switch points which normally takes place when the switch is operated from one extreme position to the other. The lock washers 15 serve to prevent rattling of the parts which might cause wear.

It should be particularly pointed out that the swivel joint thus formed is such that it cannot swivel about a horizontal axis, whereby the switch points are prevented from rolling. It should also be pointed out that the parts of the swivel joint thus formed are all designed so that they may be made using forging dies and thus obtain accurate contours without machining.

It will be noted that the bearing brackets 12 associated with the head rod 6 are bolted to the switch points on opposite sides of the offset portion, whereas the bearing brackets associated with the front rod 5 are bolted to the switch points on one side of the offset portion. This difference in construction is necessitated by the fact that it is desirable to secure the bearing brackets associated with the front rod to the extreme tips of the points. These tips are usually disposed directly over a tie, as shown, and there would be insufficient clearance for the front rod 5 and lock rod 8 if the type of bracket associated with the head rod 6 were used.

When point detection is required, the free end of the bracket 12 which is secured to the tip of the normally closed switch point may be provided with a spherical surface 12e for the reception of a point detector rod connection, such for example as that shown in my Patent No. 2,208,449, granted July 16, 1940, for Railway switch box connections. With this type of connection switch point creepage will not cause binding.

It should further be pointed out that the switch brackets which connect the lock and operating rods with the front and head rods are so constructed that movement parallel to the track transmitted to the lock and front rods from the switch points through the connecting means embodying my invention will not cause strains in the parts and displace the lock rod at right angles to the track sufficiently to throw the lock rod notches out of alignment with the locking dogs with which they normally cooperate.

One advantage of connecting means embodying my invention is that while they are inexpensive to manufacture, they provide the flexibility which is needed to allow the required motion of the switch points without developing high stresses in the parts such as sometimes occurs when a non-swiveling type of switch rod connection is used, and at the same time they provide a joint which can be kept tight.

Although I have herein shown and described only two forms of switch rod connecting means embodying my invention, it is understood that various changes and modifications may be made therein within the scope of the appended claims without departing from the spirit and scope of my invention.

Having thus described my invention, what I claim is:

1. Connecting means for connecting a switch rod to a switch point comprising an upstanding

arm provided on the switch rod and formed with a through hole and with a vertically disposed semicylindrical bearing surface on the side nearest the switch point, a bearing bracket bolted to the switch point and provided with a rounded offset portion formed with an elongated through hole which aligns with the hole in said arm and with an outer bearing surface which mates with the bearing surface in said arm, said offset portion also being provided with an inner bearing surface concentric to said outer bearing surface, a clamping bolt extending through the aligned holes in said arm and said offset portion and provided at one end with a head having a bearing surface which mates with said inner bearing surface and at the other end with a threaded portion, and a nut screwed onto said threaded portion for clamping said arm to said bearing bracket to connect said switch rod to said switch point in a manner which permits said rod to swivel relative to the point.

2. Connecting means for connecting a switch rod to a switch point comprising an upstanding arm provided on the switch rod and formed with a through hole and with a vertically disposed semicylindrical bearing surface on the side nearest the switch point, a bearing bracket bolted to the switch point and provided with a rounded offset portion formed with an elongated through hole which aligns with the hole in said arm and with an outer bearing surface which mates with the bearing surface in said arm, said offset portion also being provided with an inner bearing surface concentric to said outer bearing surface, a clamping bolt extending through the aligned holes in said arm and said offset portion and provided at one end with a head having a bearing surface which mates with said inner bearing surface and at the other end with a threaded portion, and a nut screwed onto said threaded portion for clamping said arm to said bearing bracket to connect said switch rod to said switch point in a manner which permits said rod to swivel relative to the point which permits said rod to swivel relative to the point, said arm, said bracket and said bolt being so constructed that they may be made using forging dies to obtain accurate contours requiring no machining.

3. Connecting means for connecting a switch rod to a switch point comprising an upstanding arm provided on the switch rod and formed with a through hole and with a vertically disposed semicylindrical bearing surface on the side nearest the switch point, a bearing bracket bolted to the switch point and provided with a rounded offset portion formed with an elongated through hole which aligns with the hole in said arm and with an outer bearing surface which mates with the bearing surface in said arm, said offset portion also being provided with an inner bearing surface concentric to said outer bearing surface, a clamping bolt extending through the aligned holes in said arm and said offset portion and provided at one end with a head having a bearing surface which mates with said inner bearing surface and at the other end with a threaded portion, a nut screwed onto said threaded portion for clamping said arm to said bearing bracket to connect said switch rod to said switch point in a manner which permits said rod to swivel relative to the point, and means formed integrally with said bearing bracket for the reception of a point detector rod socket connection.
